UNITED STATES PATENT OFFICE

131,432

DESIGN FOR A CONNECTING ROD

Frank P. Clark, St. Paul, Minn.

Application March 31, 1941, Serial No. 100,039

Term of patent 14 years

To all whom it may concern:

Be it known that I, Frank P. Clark, a citizen of the United States, residing at St. Paul, county of Ramsey, and State of Minnesota, have invented a new, original, and ornamental Design for Connecting Rod, of which the following is a specification, reference being had to the accompanying drawing, forming part thereof.

Figure 1 is a side elevational view of a connecting rod in closed position, showing my new design.

Figure 2 is a side elevational view thereof with the boxing in partly open position.

Figure 3 is an edge elevational view thereof.

The dominant features of the design reside in the portions shown in full lines.

I claim:

The ornamental design for a connecting rod, as shown and described.

FRANK P. CLARK.
